UNITED STATES PATENT OFFICE.

CHARLES A. WILLMARTH, OF DETROIT, MICHIGAN, ASSIGNOR OF ONE-HALF
TO JOHN STEVENSON, OF SAME PLACE.

SPACING DEVICE FOR WIRE FENCES.

SPECIFICATION forming part of Letters Patent No. 666,786, dated January 29, 1901.

Application filed June 15, 1899. Serial No. 720,646. (No model.)

To all whom it may concern:

Be it known that I, CHARLES A. WILLMARTH, a citizen of the United States of America, residing at Detroit, in the county of Wayne and State of Michigan, have invented 5 certain new and useful Improvements in Spacing Devices for Wire Fences, of which the following is a specification, reference being had therein to the accompanying drawings.

10 This invention relates to a tool used for spacing the line-wires of wire fences the proper distances apart and keeping them from drawing together while weaving on the stay-wires; and the invention consists in providing means to lock the tool upon the wires in its adjusted position, in providing simple means for holding the free end of the stay-wire while weaving, and, further, in generally adapting the tool to its purpose, so that it 15 will require but a minimum of time to operate it, all as more fully hereinafter described, and shown in the accompanying drawings, in which—

20 Figure 1 is an elevation of a wire fence, showing my improved device as in operation. Fig. 2 is a side elevation thereof with the parts in position as in being clamped upon the fence-wires. Fig. 3 is an enlarged perspective view of the upper end of the device. Fig. 4 is a vertical section on line $x-x$, Fig. 3. Fig. 5 is a cross-section on line $y-y$, Fig. 2. Fig. 6 is an enlarged elevation of that portion of the device to which the eccentric is secured.

25 A and B are two like bars secured in parallelism together, free to slide one upon the other a limited distance by means of transverse guiding-studs a , which are secured to the bar B and pass through slots b in the bar A, the studs a being provided with suitable heads c to hold the bars together, with washers d interposed, preferably, between the bars to make them slide very freely upon each other. The bars are correspondingly provided upon 30 their rear edges with L-shaped spacing-notches e , which, as shown, extend horizontally into the bars and thence downwardly and are adapted to receive the line-wires C of a fence. To adapt the device for all the 35 usual distances at which the line-wires of wire fences may be desired to be spaced apart,

such spacing-notches are provided in sets of two or more, preferably about a half-inch apart from each other.

Near the upper end the bar B is provided 55 with an elongated hole f , and the bar A is provided with a round hole or wire-passage g , which registers with the hole f in any position of the bar B. Below this hole g a hook-shaped lug D is secured to the bar A, which 60 lug is made large enough to serve the purpose of a handhold in operating the bar.

At any point convenient for operation is attached to the side of the bar A an eccentric-lever E by means of a fulcrum-pin i , 65 which, as shown in Figs. 5 and 6, is secured to the bar B and passes through a slot j in the bar A. Below the eccentric the bar A is provided with a projection k , upon which the eccentric is adapted to bear. 70

In practice, the parts being arranged as shown and described, they are intended to operate as follows: If the eccentric-lever E is moved into the position shown in dotted lines in Fig. 6, the two bars are free to slide 75 upon each other as far as the slots b permit it, and if the operator takes hold of the bar A alone (by using the hook D as a handhold and holding the device freely) the other bar B will assume such a position in relation 80 thereto that the notches in both bars register with each other. In this position of the parts the operator engages the device with the line-wires of the fence, so that the wires enter the full depth into the notches. This done he 85 depresses the eccentric-lever into the position shown in Fig. 2. By thus depressing the eccentric-lever as far as it will go the bar B is drawn upwardly and the notches of the two bars holding the wires are drawn apart and 90 the wires will be firmly clamped by the bars, and the device is thus firmly fastened upon the line-wires and cannot be moved from its position thereon. The operator is now weaving a stay-wire between the fence-wires 95 takes the free end of the stay-wire and after passing it through the holes f and g engages it into the hook D, thus forming a bend in the wire at l , (see Fig. 1,) which holds it fast. The operation of weaving is then 100 accomplished in the usual manner with the use of any of the known weaving-tools. After

the stay is woven to the line-wires the operator cuts off the loose end thereof at *l* with suitable nippers, and then taking hold of the eccentric-lever and throwing it up shoves the 5 spacing device along the line-wires into position for weaving the next stay-wire. In taking hold of the lever *E* and throwing it up into the position shown in full lines in Fig. 6 it will be seen that the eccentric relieves 10 the clamping-pressure. The notches of the bars still overlap. Thus while the device is free to be moved laterally upon the wires the latter cannot accidentally disengage from it. However, when it is desired to detach the device 15 from the fence (as it will have to be done when meeting a post) the operator has merely to throw up his eccentric higher, as shown in the dotted position shown in Fig. 6, when the two bars will adjust themselves with the 20 notches in coincidence, and thereby permit the device to be readily withdrawn from the wires. It will thus be seen that the operator can manage the device in operation with his one free hand, while he manages the weaving- 25 tool with the other, and thus he does not lose any time, which, considering that the cost of a fence of this character largely depends upon the speed with which the stay-wires can be put on, is of considerable importance.

30 Having the line-wires absolutely locked in position during weaving contributes greatly to making a perfect fence.

The device as herein described may also be used in fixed position, doing duty as a fence-post either temporarily while weaving the fence or permanently. It may be secured in the ground by securing it to a suitable base or making the bars simply long enough to reach a suitable distance into the ground.

35 40 What I claim as my invention is—

1. In a spacing device, the combination of two like bars secured side by side free to slide one upon the other and adapted to be engaged with the line-wires of a fence by having 45 corresponding L-shaped notches in each bar for receiving said line-wires, an eccentric

50 tric fulcrumed to one of the bars the fulcrum pin of which projects through and has a limited movement in the slot *j* independently of the other bar and having a lever-handle for turning it, and a bearing on the other bar with which said eccentric is adapted to engage and cause a relative sliding movement between the bars for clamping the fence-wires by overlapping the notches in the bars. 55

2. In a spacing device, the combination of the two like bars *A*, *B* secured side by side free to slide one upon the other, the inwardly and downwardly extending notches along the edges of the bars arranged in sets at intervals corresponding to the line-wires of the fence, the eccentric *E* fulcrumed to one of the bars, the bearing *k* for said eccentric on the other bar, the apertures *g* and *f* in the bars for the passage of the stay-wires, and the 60 hook *D*. 65

3. A wire-fence spacer comprising the parallel bars, *A*, *B*, adjustably secured together and provided with L-shaped notches for receiving the line-wires of a fence, an eccentric 70 having a lever-handle pivotally secured to one of the bars and operating on a bearing *k* on the other bar to lock the spacer-bar on the line-wires of a fence, and the hook *D* for the stay-wire. 75

4. In a spacing device, the combination of the two bars *A*, *B*, secured side by side free to slide one upon the other, inwardly-extending notches formed along the edges of the bars, arranged in sets at intervals corresponding to the line-wires of the fence, the eccentric *E* fulcrumed to one of the bars and having a lever-handle, the bearing *k* for said eccentric on the other bar, and the clamping-screws *a* whereby the parts may be clamped 80 in any of their adjusted positions. 85

In testimony whereof I affix my signature in presence of two witnesses.

CHARLES A. WILLMARTH.
